[57] CLAIM

The ornamental design for a mud guard, as shown.

DESCRIPTION

FIG. 1 is a front elevational view of the mud guard
showing our new design;

FIG. 2 is a top plan view thereof;

FIG. 3 is a right side elevational view thereof;

FIG. 4 is a bottom plan view thereof;

FIG. 5 is a left side elevational view thereof;

FIG. 6 is a cross-sectional view thereof taken along line
6—6 of FIG. 1;

FIG. 7 is a cross-sectional view thereof taken along line
7—7 in FIG. 1;

FIG. 8 is a cross-sectional view thereof taken along line
8—8 in FIG. 1;

FIG. 9 is a cross-sectional view thereof taken along line
9—9 in FIG. 1;

FIG. 10 is a cross-sectional view thereof taken along
line 10—10 in FIG. 1;

FIG. 11 is a cross-sectional view thereof taken along
line 11—11 in FIG. 1; and,

FIG. 12 is a cross-sectional view thereof taken along
line 12—12 in FIG. 1.

Fig. 1.
